UNITED STATES PATENT OFFICE.

JULIUS M. BREITENBACH, OF NEW YORK, N. Y.

STRETCHER-SUPPORT.

1,312,516.

Specification of Letters Patent. Patented Aug. 12, 1919.

Application filed August 23, 1918. Serial No. 251,188.

To all whom it may concern:

Be it known that I, JULIUS M. BREITENBACH, a citizen of the United States, residing at New York city, in the county of New 5 York and State of New York, have invented new and useful Improvements in Stretcher-Supports, of which the following is a specification.

This invention is a stretcher support, and 10 important objects of the invention are to facilitate the loading and unloading of wounded lying upon stretchers; to adapt the device for the support of standard army stretchers; to provide an effective elastically 15 yieldable support for the stretchers in order to compensate as far as possible for jolting movements of the truck; to provide for the convenient transportation of a relatively large number of wounded soldiers who can 20 sit up and do not require stretchers; and to embody the invention in the form of an attachable super-structure capable of being readily set up upon the platform of any platform type of truck, and to enable the convenient removal and ready collapse of the 25 structure into small compass for transportation and storage.

With these and other objects in view, the present invention consists in the combination 30 and arrangement of parts, as will be herein-after described, shown in the accompanying drawings, and particularly pointed out in the appended claims, it of course being understood that changes in the form, proportion, size and minor details may be made, 35 within the scope of the claims, without departing from the spirit or sacrificing any of the advantages of the invention.

In the drawings, 40 Figure 1 is a perspective view of a truck equipped with the structure of the present invention.

Fig. 2 is an enlarged fragmentary detail taken on the line 2—2 of Fig. 1.

Fig. 3 is a side elevation of Fig. 2, parts of one of the rails being broken away.

Fig. 4 is a plan section on the line 4—4 of Fig. 2.

Fig. 5 is a fragmentary detail plan view 50 of one end of the seat.

Fig. 6 is an end elevation of Fig. 5.

In the accompanying drawings 1 designates the platform of any desired type of platform truck, which may be self propelled,

55 as for instance an electric truck, but it will of course be understood that any type of

truck and any form of power may be employed, as the present invention does not reside in the truck *per se*.

As hereinbefore indicated, the present invention is embodied in the form of a super-structure and includes four corner posts or uprights, two corner posts, designated 2 being located at the front of the truck and two corner posts designated 3 being located at 60 the rear of the truck. These posts are duplicates and are in the form of cylindrical metallic tubes or pipes of suitable dimensions according to the size of the truck. Each post or upright is provided at its lower 65 end with an elbow 4 having its horizontal member directed inwardly with respect to the truck and connected to a short horizontal pipe section 5, which in turn is provided at its inner end with a downwardly directed 70 elbow 6 extending downwardly through a suitable opening or socket 6' in the adjacent corner section of the platform of the truck. By means of the elbows 4 and 6 and the short length of pipe 5, the corner posts may be 75 spaced a greater distance than if they extended directly upward from the corners of the platform. By this arrangement the maximum width between corner posts is obtained. Midway between each front post 2 is 80 a front intermediate post 7, and intermediate the rear post 3 is an intermediate rear post 8. Each of the intermediate front and rear posts 7 and 8 has its lower end fitted into a 85 suitable socket or opening in the platform of 90 the truck, and has a suitably snug engagement therewith so as to stand alone when fitted in place. Each intermediate post is provided at its upper end with a T coupling 9, and between each corner post and each intermediate post there is a top cross-bar 10, 95 the inner end of which is fitted to the adjacent end of the T coupling 9. The outer end of each top cross bar 10 is connected to the adjacent corner post by a suitable elbow 11. 100 Across the top of the structure extend diagonal braces 12. Each brace is preferably a wire rope having its ends suitably connected to the diagonally opposite upper corners of the front and rear frames, and including a 105 turnbuckle 12', whereby the top portions of the front and rear frames may be drawn together so as to tighten the frame and maintain it in a rigid condition as will herein-after appear.

As illustrated in the present drawings, 110 the device is adapted for the support of four

stretchers, and as the stretcher supports are duplicates in construction, a description of one of them is deemed sufficient. Each stretcher support includes a pair of longitudinally disposed rails 13 extending the entire length of the device in the same horizontal plane and inclined downwardly from the front to the rear of the frame. As best illustrated in Fig. 2, it will be seen that the rail 13 is in the form of a channel bar having at its lower side inwardly directed flanges 14 terminating in upwardly directed flanges 15, which flanges, together with the side walls of the rail define guideways for a purpose as will be hereinafter described. Each end of each rail is supported in a hanger made up of complementary bracket members 16 and 17 which jointly embrace the rail and are provided with upstanding shank portions 18 and 19 which lie against one another and are located at the inner side of the adjacent post or upright, to which the hanger is pivotally connected by means of a suitable fastening, as for instance a bolt 20 extending through the post and the shanks and provided with a nut 21. The hangers at the rear of the device are provided with an additional member 22 embracing the member 16 and provided with an upper shank portion 23, pierced by the bolt 20, and also provided on its lower arm or member with a hook 24 disposed beneath and opposite the middle of the rail. Each hanger is pivoted to its post in order that it may be swung or tilted outwardly to enable the introduction of the adjacent end of the rail 13, after which the hanger is moved inwardly into its normal upright position. It is preferred to have the bolt 20 hold the hanger with a considerable degree of rigidity or stiffness, such as to require the blows of a hammer or the like to move the hanger outwardly and thereafter to drive the hanger back upon the adjacent end of the rail 13 and into its normal upright position alongside of the post or upright. To prevent the end of the rail 13 from being driven through the hanger, the latter is provided with a substantially U-shaped clip 25 of bendable sheet metal, the arms of the clip being provided with terminal hooks 26 which embrace the inner edges of the hanger members 16 and 17, as best shown in Fig. 4 of the drawings, whereby the intermediate or head portion of the clip closes the outer end of the hanger and constitutes the stop against which the end of the rail engages. A suitable spring suspension device 27 hangs from the hook 24 of each rear hanger, and this suspension is provided at its lower end with a suitable hook 28. A duplicate suspension and hook 29 and 30 are mounted to travel upon each rail, in the manner best shown in Fig. 3 of the draw-

ings. The upper end of the spring suspension 29 is engaged with the hook 31 on the lower end of a headed bolt or shank 32 swiveled in a crosshead 33, which is provided at each end with a pair of rollers 34 traveling on the track portions 14 of the rail.

As best indicated in Fig. 3, it will be noted that the rail 13 inclines downwardly and rearwardly, one purpose of which is to cause the spring suspension 29 to gravitate to the rear end of the device in order that it may always be in position for engagement with the handles of the stretcher when loading a stretcher upon the device.

In using the device for stretcher cases, the suspension members 29 being at the lower ends of the rails, and therefore at the rear of the device, the stretcher bearers at the head of the stretcher engage the handle bars with the hooks 30, and then the stretcher bearers at the foot of the stretcher push the stretcher forwardly, such movement being permitted by reason of the slideable mounting of the suspension member 29 in the rails 13. When the stretcher has reached its proper position, the hooks 28 of the fixed rear suspension devices 27 are engaged with the rear handle bars of the stretcher, and the latter is then supported in place. The stretcher cannot become endwise displaced for the reason that the rear suspension devices 27 are secured to the fixed hooks 24 and the handle bars are tapered and wedge in the hooks. Furthermore the suspension members 29 cannot travel out of the upper and forward ends of the rails 13 because of the presence of the clips 25. To remove a stretcher, the hooks 28 are disengaged from the stretcher handles and the stretcher is then drawn rearwardly, this movement being permitted by reason of the traveling or slideable mountings of the suspension member 29. When the suspension members 29 reach the rear end of the device, the handle bars at the front of the stretcher are grasped and withdrawn endwise from the hooks 30, or the hooks 30 may be disengaged from the handle bars as desired.

It will here be explained that the stretchers *per se* form no part of this invention, and may be of any desired type so long as they are provided with terminal handle bars capable of being engaged by the hooks of the suspension members.

As illustrated in the accompanying drawings, the device is arranged for four stretchers, but a greater or less number could be employed according to the size of the device.

For transporting wounded who are able to sit up, I have equipped the device with a double seat 35 which normally rests upon the platform 1 of the truck and is provided

at each end with a notch or seat 36 to receive the adjacent intermediate posts, as plainly indicated in Figs. 5 and 6 of the drawings, whereby the seat is held in place. The seat is provided at each end, and also at its middle, if desired, with foldable legs 37, which, when swung down into supporting position, as indicated in Fig. 6, will support the seat at the desired elevation. The width of the seat with respect to the distance between the opposite corner posts 3 is such that a number of persons may be accommodated at opposite sides of the seat, the lowermost rails 13 supported by the intermediate posts 7 and 8 forming a suitable back. It will of course be understood that the stretchers are not in place when the seat is in use, and when the stretchers are in place the seat is lowered to the position shown in Fig. 1 and therefore does not interfere with the stretchers. In the embodiment of the device as illustrated for four stretchers, the length is such that the seat or bench will accommodate ten persons, five at each side of the seat.

When the stretchers are not in place, the truck may be employed for transportation purposes generally, and the entire framework may be conveniently removed in order to afford a truck with an unobstructed platform or for the purpose of collapsing the frame for convenience in transportation and storage.

What I claim is:

1. A stretcher support comprising a frame including guideways, individual stretcher suspension devices fixed with respect to the guideways, and other individual stretcher suspension devices mounted to travel upon the guideways, the suspension devices of one guideway being independent of the suspension devices of each other guideway.

2. A stretcher support comprising uprights, rails upon the uprights, each rail being hollow and provided with a longitudinal slot in the bottom thereof and constituting a guideway, stretcher suspension devices hung from corresponding ends of the rails; and other stretcher suspension devices having wheeled members within the respective rails and traveling upon the guideway portions thereof.

3. A stretcher support comprising a frame including guideways, individual stretcher suspension devices fixed with respect to the guideways, and other individual stretcher suspension devices mounted to travel upon the guideways, each suspension member including a spring coil provided at its lower end with a hook for engagement with a stretcher handle bar, and the suspension de-

vices of one guideway being independent of the suspension devices of each other guideway.

4. A stretcher support comprising uprights, hangers carried upon the uprights 65 and mounted for movement upon horizontal axes, rails having their ends supported in the hangers, and stretcher suspension devices carried by the rails.

5. A stretcher support comprising uprights, hangers upon the uprights, rails supported by the hangers, stretcher suspension devices carried by the rails, and a tie device connecting the front and rear posts and including a turnbuckle. 75

6. A stretcher support comprising uprights, hangers upon the uprights, rails supported by the hangers, a set of stretcher suspension devices carried by one set of hangers, and another set of stretcher suspension devices mounted to travel upon the rails. 80

7. A stretcher support comprising front and rear uprights, a pair of rails supported by the uprights at an angle thereto other than a right angle, a set of stretcher suspension devices at the lower ends of the rails, and another set of stretcher suspension devices mounted to travel upon the rails and capable of graviting to the lower ends 90 thereof.

8. The combination with a truck having a platform, of corner uprights and front and rear intermediate uprights, front and rear crossbars connecting respective front and rear uprights, each corner upright being provided with an inwardly directed offset lower portion engaged with the platform, pairs of rails extending between front and rear uprights, fixed stretcher suspension devices at the rear ends of the rails, other stretcher suspension devices mounted to travel upon the rails, and diagonal ties connecting the tops of the corner uprights and including turnbuckles. 95 100 105

9. The combination with a wheeled truck, of corner and intermediate uprights rising therefrom, rails connecting front and rear uprights, stretcher suspension devices carried by the rails, and a seat supported upon the platform and provided at opposite ends with recesses receiving the respective front and rear intermediate uprights, said seat being provided with collapsible legs, whereby the seat may rest in a lowered inoperative position on the platform and also be raised to an operative position with its legs resting upon the platform. 110 115

JULIUS M. BREITENBACH.
